UNITED STATES PATENT OFFICE

2,603,891

SLIPPER

Gustav Cohn, New York, N. Y.

Application May 10, 1950, Serial No. 161,158

5 Claims. (Cl. 36—9)

1

This invention relates to a slipper, and more particularly to a washable slipper having a crocheted upper provided with lacing means anchored to the sides of the sole of said shoe, and wherein the top sole, heel wedge, inner and bottom soles are laminated to produce a unitary type of footwear.

In various types of footwear, particularly where the uppers are made of textile or fabric material, it will be noted that the soles of said type of footwear are of such a quality that in time they deteriorate rather quickly. Also, such types of footwear become soiled very easily and cannot be washed, with the result that within a short time they are discarded. Furthermore, the uppers of said types of footwear are usually made of canvas or other non-yieldable material, while the lower or foot resting portion is made up of a number of separate parts which, upon washing, will fall apart.

In accordance with my invention, it is desired to provide washable footwear having a flexible elastic upper adapted to provide a certain amount of elasticity whereby the footwear readily conforms to the size and shape of the foot of the wearer.

It is accordingly, an object of this invention, to provide a novel type of easily assembled footwear whose parts are formed into a unitary non-separable flexible product.

Another object of the present invention is to provide a washable slipper having its component foot supporting parts laminated into a unitary mass in which the sole and heel portion thereof are indistinguishable one from the other.

One other object of the present invention is to provide a slipper having a crocheted lastex upper anchored to the marginal edge of the intermediate sole which in turn is fused to an inner and outer sole so as to form a unitary, integral slipper.

A more specific object of the present invention is to provide a washable unitary slipper in which the marginal edge of the inner sole is provided with a series of hidden or sealed holes having a chain or lock stitch extending therefrom onto the marginal edge of the sole to permit easy anchoring thereto of a crocheted upper by means of any suitable stitch, which is adapted to conform with the shape and size of the foot of the wearer.

Another object of the present invention is to provide a novel, economic method of forming anchoring means in the sole of a slipper and of laminating the component parts thereof to form a washable type of slipper.

Further features and objects of the present

invention will become apparent from the following description taken in connection with the accompanying drawings, in which:

Fig. 1 is a side elevation of a preferred embodiment of the present invention;

Fig. 2 is a plan partly broken away view of the bottom of the intermediate sole showing the type of stitching utilized for the purposes of anchoring a flexible upper thereto as hereinafter described;

Fig. 3 is a perspective fragmental detailed view of the portion shown in Fig. 2;

Fig. 4 is a fragmental detailed sectional view taken on line 4—4 of Fig. 1; and,

Fig. 5 is a longitudinal sectional view of the foot supporting portion of the embodiment prior to lamination of the parts thereof.

Referring now more particularly to the drawings in which similar reference numerals refer

20 to like parts throughout, there is provided a slipper 10, having a hand-crocheted upper 11 of any suitable style or design. The upper 11 is made preferably of an elastic flexible type of synthetic yarn such as "nylon" or "orlon," such as disclosed in United States Patent 2,387,320 issued October 23, 1945, in the name of Foster, mixed with nylon thread or any other suitable textile yarn. In the manufacture of my new type of footwear said upper 11 is crocheted as a complete unit preparatory to its connection to the lower

25 30 laminated foot supporting portion 12. Said foot supporting portion 12 as shown in Fig. 1 of the drawings is made of several parts which are laminated together in any suitable manner either by thermosealing or by cementing the same with

35 any suitable type of adhesive material, such as rubber cement.

It will be noted that foot supporting portion 12, prior to lamination, as shown more specifically in Fig. 5, furthermore, contains an outside

40 or bottom sole 13, made of any suitable flexible material, such as leather or "neelite," an intermediate sole 14, a wedge heel 15 and an inner sole 16, provided with a sock lining 17 on its upper

45 sole 16, provided with a sock lining 17 on its upper surface. Said intermediate sole 14, wedge heel 15 and inner sole 16 are preferably made of a mixture of cork and rubber and lend themselves to easy lamination or thermosealing so as to form a unitary foot supporting flexible portion 12, as shown more clearly in Fig. 1.

50 Prior to the lamination of said parts, intermediate sole member 14 is perforated and provided with a plurality of holes or openings 18 arranged in series along the marginal edge 19 of said sole member 14. Said holes are evenly spaced along the periphery of said sole member

14 but are set inwardly of said edge sufficiently far to permit covering and sealing of said holes when forming the completed foot resting portion 12 and to be sealed from view when the sole is laminated. Furthermore, by means of said holes 18, an overedge chain stitch 20 may be formed extending continuously and horizontally from the marginal edge 19 of the intermediate sole 14 as clearly shown in Fig. 3. This type of chain stitch provides an anchor to which there is attached by means of thread or lace 21 the crocheted upper 11. The thread or yarn used to make chain stitch 20 may be of "nylon" or other suitable strong thread or fiber material which will resist wear and tear and continued washing.

In the process of making the slipper, the soles 13, 14, and 16 are initially swabbed with rubber cement and laid over each other with or without the wedge heel 15 between the rear portion of the inner and intermediate soles so that the marginal edges of each of these members are even with each other leaving only the chain stitch 20 protruding from the intermediate sole 14. These members are then laminated together by the application of heat and pressure, whereby all of the parts are welded so as to make an integral laminated foot supporting portion. After said foot supporting portion has been made the upper 11 is then anchored to the chain stitch 20 in any suitable manner, for example as by an auxiliary stitching 21 as shown in Figs. 1 and 4.

From the foregoing description taken in conjunction with the accompanying drawings, it will be noted that by my invention a suitable flexible type of footwear can be made in three sizes; small, medium and large, particularly of the slipper type, thereby obviating the necessity of making slippers according to the exact footsize. Also, by making such types of footwear in the three sizes indicated, considerable savings in cutting according to different lasts is effected. By the use of an upper in footwear made according to the present invention, it will be noted that such upper has a certain amount of elasticity so as to conform with the shape and size of the foot of the wearer. In other words, this type of footwear is adjustable to different foot sizes.

Furthermore, according to my invention, it will be noted that the anchoring means or chain stitch 20 protrudes from holes or openings 18, and extends horizontally from the margin of the intermediate sole member 14 and is intermediate the inner and outer soles. There is no danger of the chain stitch forming any contact with either the foot of the wearer or with the surface upon which the wearer of the slipper walks. In addition, said type of stitch 20 forms a part of the laminated foot supporting portion, thereby eliminating any possibility of said stitching being broken. The openings 18 in intermediate sole 14 are not only hidden from view but are also filled due to the lamination of sole member 14 with sole members 13 and 15.

It will also be noted that a footwear made according to the present invention has long wearing qualities, does not readily deteriorate and can be easily washed without any breakdown of the ingredients of the foot resting portion. Nor will footwear made according to the presently disclosed invention crumble or fall apart when exposed to dampness or washed.

While a preferred embodiment of the invention has been disclosed, it will be noted that modifications as to arrangement of parts, use of materials and the procedure of their use may be

made without departing from the spirit and scope of the invention as claimed.

I claim:

5 1. In a shoe the combination comprising a sole defined by at least three layers; a plurality of loops arranged along the edge of said sole, each of said loops having a portion thereof extending vertically through an intermediate layer adjacent the edge of the latter, portions extending outwardly from said first mentioned portion and being concealed between said intermediate layer and the next adjacent layers, and a portion overlying the edge of said intermediate layer; an upper; and fastening means securing said upper to those portions of said loops overlying the edge of said intermediate layer.

15 2. The structure defined in claim 1 in which the loops comprise chain stitches.

20 3. In a shoe the combination comprising a laminated sole having at least three laminations, a plurality of loops arranged along the edge of said sole, each of said loops extending vertically through a marginal edge portion of an intermediate lamination, outwardly between said intermediate lamination and the next adjacent laminations, and around the edge of said intermediate lamination, an upper, and flexible means securing said upper to those portions of said loops extending around the edge of said intermediate lamination.

35 4. A flexible slipper comprising a laminated sole having at least three laminations secured together into a unit, a plurality of chain stitches extending through and arranged along the marginal edge portion of an intermediate lamination, each of said stitches passing vertically through said edge portion, between said intermediate lamination and the next adjacent laminations, and around the edge of said intermediate lamination, an upper, and lacing means securing said upper to those portions of said stitches passing around the edge of said intermediate lamination.

40 5. In a shoe, the combination comprising a plurality of laminations, a marginal, continuous stitch extending laterally of the laminated sole, but short of the heel supporting portion thereof, and forming a plurality of successive loops comprising chain stitches along the edge of said sole, each of said loops extending vertically through a marginal edge portion of an intermediate lamination, outwardly between said intermediate lamination and the next adjacent laminations, and around the edge of said intermediate laminations, an upper, and flexible means securing said upper to those portions of said loops extending around the edge of said intermediate lamination.
